UNITED STATES PATENT OFFICE.

JOSEPH H. BURKE, OF PORTLAND, MAINE.

SAW-GUARD.

1,383,285.

Specification of Letters Patent.

Patented July 5, 1921.

Application filed May 22, 1920. Serial No. 383,380.

To all whom it may concern:

Be it known that I, JOSEPH H. BURKE, a citizen of the United States, residing at Portland, in the county of Cumberland and 5 State of Maine, have invented certain new and useful Improvements in Saw-Guards, of which the following is a specification.

My invention relates to saw guards for protecting circular saws and the invention 10 is particularly directed to an improved construction of the saw guard as shown in my application No. 337,074, filed Nov. 10, 1919.

In the above named application I made use of a depending hollow tube which held a 15 rod, on the lower end of which was a lateral projection terminating in a depending bar or rod which supported on its lower end the hood or saw guard proper.

The device was so constructed that the 20 vertical rod could slide vertically and revolve in the supporting tube so that the guard could be lifted with one hand, turned to a position entirely removed from the saw and clamped in its new position by the other 25 hand of the operator, making a quick and easy adjustment.

The difficulty with this device was that when the hood which covered the saw was placed sufficiently low to just clear the upper 30 surface of the stock, which was its preferable position, any increase in thickness of the stock was liable to cause it to bind on the lower edge of the hood and thus interfere with the free operation of the saw.

According to my present invention I 35 mount the hood in such a way as to have a free vertical motion so that all binding by the stock is prevented as the guard is automatically lifted when an extra thickness is 40 run through the saw.

As I preferably construct the device the weight of the guard and its attached parts are partially counter-balanced so that the 45 guard is easily lifted but it has sufficient weight to keep a light pressure on the top of the stock at all times.

I have illustrated my invention in the accompanying drawing in which is shown a saw guard embodying the preferable form 50 of my invention.

In the drawing:

Figure 1 is an elevation looking at the saw edge-wise and, Fig. 2 is an elevation taken at right angles to Fig. 1.

55 Referring to the drawing:

1 indicates the depending hollow tube by

which the device is supported, 2 is the supporting rod fitting in the tube 1 and rotatable and slideable in said tube, 3 is the hand clamp, 4 is the saw, 5 is the machine table 60 and 6 is the hood or saw guard proper.

These parts are all substantially the same as set forth in my said application.

According to my present invention, as here shown, I secure to the top of the hood 65 6 a supporting bar 7 which passes through a vertical socket 8 secured to the end of the offset which projects from the lower end of the rod 2.

The rod 7 is square where it passes through 70 the sleeve or socket 8 to prevent lateral turning. A pin or stop 9 holds the bar 7 and the hood from dropping onto the table and the whole apparatus may be raised and lowered by raising or lowering the rod 2 and clamp- 75 ing it in position by the clamp 3.

The hood and its bar 7 are partially counter-balanced by a cord 10 and weight 11, the cord passing over a pulley or truck 13 pivoted on an arm 12 which extends out 80 from the tube 1 or other suitable support.

The principal weight is thus lifted from the hood and bar and the hood will in use rest lightly on the stock as it passes through the saw but will readily lift when work of 85 extra thickness passes through.

One great advantage of this arrangement is that the hood rests always on the work holding the same down and in position so that the saw does not have to be kept clear 90 of strips as they are sawed as under the old arrangement, for fear that the strip will be caught by the saw and thrown.

Thus when a number of strips are fed in one after another no attention need be paid 95 to see that the saw is always clear as the weight of the hood holds them firmly in place.

The hood may be raised and swung out of the way as in my old device and the present 100 device has the additional advantage of taking various thicknesses and of holding the work down.

The front end of the hood is slightly turned up so as to readily admit strips of 105 greater thickness than the guard is set for.

A plurality of holes may if desired be made in the bar 7 to receive the pin 9 so that the bar and the hood may be stopped in different positions to conform to the thickness 110 of the stock passing through the saw. There are thus two means of vertical adjustment,

the pin 9 and the rod 2 held in place by the clamp 3.

I claim:

1. In a saw guard mechanism, the combination of a depending post, a rod slidably and rotatably connected with its lower end, said rod having a lateral offset at its lower end, a vertical socket on said offset, a sliding bar in said socket, a hood carried by said bar, an arm projecting from said post, and a cord and counter-weight connected with said arm for partially counter-balancing the weight of said bar and guard.
- 10 2. In a saw guard mechanism the combination of a depending post, a rod slidably and rotatably connected with its lower end, said rod having a lateral offset at its lower end, a vertical socket on said offset, a sliding bar in said socket, a hood carried by said bar, an arm projecting from said post, and a cord and counter-weight connected with said arm for partially counter-balancing the weight of said bar and guard.

nation of a depending post, a rod slidably and rotatably connected with its lower end, 15 said rod having a lateral offset at its lower end, a vertical socket on said offset, a sliding bar in said socket, a hood carried by said bar, an arm projecting from said post, and a cord and counter-weight connected with said arm for partially counter-balancing the 20 weight of said bar and hood.

In testimony whereof I have affixed my signature.

JOSEPH H. BURKE.
